(57) **CLAIM**

The ornamental design for a motor housing for grass cutter,
as shown and described.

DESCRIPTION

FIG. 1 is a front, left and top perspective view of a motor housing for grass cutter showing our new design;

FIG. 2 is a rear, left and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, left and top perspective view of the motor housing for grass cutter in accordance with our new design illustrating a state in which environmental structures (a cutting head, a guard, a shaft, a handle attachment, an operation handle, and a battery) are attached to the motor housing for grass cutter.

The broken lines in the drawings illustrate the environmental structures or portions of the motor housing for grass cutter which form no part of the claimed design.
